Primary Examiner — Richard E Chilcot(74) *Attorney, Agent, or Firm* — NSIP Law**(57) CLAIM**

I claim the ornamental design for a display screen or portion thereof with graphical user interface, as shown and described.

DESCRIPTION

The sole FIGURE is a front view of a display screen or portion thereof with graphical user interface showing my new design. The broken line showing of a device illustrates environment and the remainder of the broken lines represent portions of the display screen or portion thereof with graphical user interface; the broken lines form no part of the claimed design.
